UNITED STATES PATENT OFFICE.

JOHN K. STEWART, OF CHICAGO, ILLINOIS; JULIA B. STEWART EXECUTRIX OF SAID
JOHN K. STEWART, DECEASED.

LADLE FOR DIE-CASTING MACHINES.

1,219,359.

Specification of Letters Patent. Patented Mar. 13, 1917.

Application filed January 5, 1916. Serial No. 70,380.

To all whom it may concern:

Be it known that I, JOHN K. STEWART, a citizen of the United States, residing at Chicago, in the county of Cook and State of Illinois, have invented new and useful Improvements in Ladles for Die-Casting Machines, of which the following is a specification, reference being had to the accompanying drawings, forming a part thereof.

10 This invention relates to means for feeding molten metal from a melting pot or other heated container to a suitable die or mold with the aid of air pressure, and has for its purpose the minimizing of the quantity of metal exposed at any one time to such air pressure with a view to minimizing the oxidation of molten metal from this cause. It consists of the features and elements described and shown in the drawings as indicated by the claims.

15 20

In the drawings:

Figure 1 is a vertical section showing a melting pot and ladle therein embodying this invention.

25 Fig. 2 is a transverse vertical section taken as indicated at line 2—2 on Fig. 1.

The construction illustrated in the drawings comprises the usual retort or heating chamber, A, fitted with gas burners, B, and supporting a melting pot, C, which contains the main body of molten metal shown at D. Within the melting pot, C, there is mounted on trunnions, E¹, a ladle member, E, whose containing chamber is in the form of a conduit, E², leading from a discharge mouth, E³, back into and through one of the trunnions, E¹, to a suitable coupling with the source of compressed air not shown. In addition to the portion containing the conduit, E², the ladle member is provided with a stiffening rib, E⁴, and as a continuation of that rib there is a portion forming a segmental gear, E⁵, concentric with the trunnions, E¹. A rock shaft, F, is provided with a pinion, G, meshing with the segmental gear, E⁵, and through a rocker arm, H, and connecting rod, J, is arranged for actuation by any suitable source of power, not shown.

Within the melting pot, C, there is fixedly mounted a discharge nozzle, K, having an oblique inner terminal formed to connect with the discharge mouth, E³, of the ladle, E, and whose outer end is adapted for registration and connection with the molding die shown at L. Assuming the ladle member as being first in the position indicated in

dotted lines in Fig. 1, it will be seen that its cavity, E², will fill with the molten metal, D, in the melting pot, C, substantially up to the level of such metal in the melting pot itself, so that when the die, L, has been moved into connection with the discharge nozzle, K, the ladle member, E, may be rotated to the position shown in full lines in Fig. 1, so that the metal contained in its cavity, E², will be isolated from the remainder of the molten metal, D, in the melting pot, C. Thus the compressed air when applied through the hollow trunnion, E¹, will have no opportunity to oxidize the principal supply of metal as is the case in many constructions now in use in which the air pressure is applied to the surface of a larger body of metal. The pressure thus furnished will serve to force the contents of the cavity, E², through the discharge nozzle, K, and into the die, L, completely filling all recesses of the die to form the desired casting. The air pressure being then shut off, the ladle member, E, may be rotated back to the position shown in dotted lines for refilling for the next casting.

It will be seen that when the ladle, E, is rotated to discharging position with its mouth, E³, abutting the oblique terminal of the nozzle, K, the actuating rod, J, is in tension, and to avoid the necessity of extreme accuracy in the connections and their movements this rod is coupled yieldingly to the rocker arm, H, through a compression spring, M. The end of the rod having a cross pin, N, telescopes into a tubular member, O, slotted at O¹, for protrusion of the pin, N, and to permit the pin to engage the end of the compression spring, M, through an interposed washer, T, slidably mounted on the tubular member, O. The opposite end of the spring, M, reacts against a flange, O², of the tubular member, O, through which it transmits the pull of the rod, J, to the terminal, O³, which is pivoted to the end of the rocker arm, H. For reverse movement for swinging the ladle to the position shown in dotted lines the pin, N, engages directly against the other flange, O⁴, of the member, O, and no yielding connection is necessary since exactness of position of the ladle at this limit of its movement is not so important.

I claim:

1. The combination of a receptacle for molten metal, having a discharge nozzle,

of a ladle device having a cavity and a mouth adapted to receive a charge of molten metal and to discharge the same, said ladle device having also connections for supplying compressed air to the cavity for discharging the metal therefrom to the mouth and for moving the ladle device in said receptacle to carry said discharge mouth into and out of registration with the discharge

10 nozzle.

2. In a receptacle for molten metal, a ladle device mounted for movement therein, a fixed discharge nozzle for the receptacle, the ladle having a cavity with a mouth positioned to be submerged in the molten metal at one limit of movement of said ladle and adapted to connect with said nozzle at the other limit of such movement, together with a connection for admitting compressed air 20 to the cavity to discharge the molten metal therefrom.

3. In a receptacle for molten metal, a ladle device mounted for movement therein, a fixed discharge nozzle for the receptacle positioned above the level of the molten metal therein, the ladle having a cavity with a mouth adapted to be submerged in the molten metal at one limit of movement of said ladle and adapted to connect with the nozzle 30 at the other limit of such movement, together with a connection for admitting compressed air to the cavity when said mouth is connected with said nozzle for effecting discharge of the molten metal from the cavity through 35 said nozzle.

4. In a receptacle for molten metal, a ladle device mounted to rotate therein, and a fixed discharge nozzle for the receptacle, said ladle having a cavity with a mouth positioned to be submerged in the molten metal at one limit of its rotative movement, and adapted to register with said nozzle at the other limit of such movement, together with a connection for admitting compressed air to 45 the cavity to discharge the metal therefrom.

5. In a receptacle for molten metal, a ladle device mounted on trunnions to rotate in said receptacle, and a fixed discharge nozzle for the receptacle, said ladle having a cavity with a mouth positioned to be submerged in the molten metal at one limit of its rotative movement, and adapted to register with said nozzle at the other limit of such movement, together with a connection leading through one of said trunnions to the ladle cavity for admitting compressed air to discharge the molten metal therefrom through said nozzle.

6. The combination of a receptacle for 60 molten metal, a discharge nozzle therefor, a ladle device having a cavity and a mouth therefor adapted to admit a charge of the molten metal to the ladle cavity, together

with a connection for supplying compressed air to said cavity for discharge thereof, and 65 means for relatively moving the ladle member and the nozzle into connection to effect such discharge through said nozzle, said means including a yielding member whereby the connection between the ladle member and 70 the nozzle is yieldingly maintained during discharge of the metal therefrom.

7. The combination of a receptacle for molten metal, a discharge nozzle therefor, a ladle device having a cavity and a mouth 75 therefor adapted to admit a charge of the molten metal to the ladle cavity, together with a connection for supplying compressed air to said cavity for discharge thereof, and means for relatively moving the ladle member and the nozzle into connection to effect such discharge through said nozzle, said means comprising gear teeth on one of said parts, a rock shaft having a pinion positioned to mesh with said teeth, and means 80 for rotating the rock shaft to effect the relative movement of the said parts.

8. In a receptacle for molten metal, a ladle device mounted to rotate therein, and a fixed discharge nozzle for the receptacle, 90 said ladle having a cavity with a mouth positioned to be submerged in the molten metal at one limit of its rotative movement, and adapted to register with said nozzle at the other limit of such movement, together with 95 a connection for admitting compressed air to the cavity to discharge the metal therefrom, and means for effecting the rotation of the ladle member comprising a segmental gear rigidly associated therewith, a rock 100 shaft, a pinion on said shaft positioned to mesh with said gear, and means for rotating the rock shaft in either direction at will.

9. In a receptacle for molten metal, a ladle device mounted to rotate therein, and 105 a fixed discharge nozzle for the receptacle, said ladle having a cavity with a mouth positioned to be submerged in the molten metal at one limit of its rotative movement, and adapted to register with said nozzle at the 110 other limit of such movement, together with a connection for admitting compressed air to the cavity to discharge the metal therefrom, and means for effecting the rotation of the ladle comprising a gear rigidly associated therewith, a rock shaft, a pinion on said rock shaft positioned to mesh with said gear, a crank arm on the rock shaft, and a link connected to said crank arm, said link being yieldingly extensible in the direction 115 of its movement which effects registration of the ladle mouth with the discharge nozzle.

In testimony whereof I have hereunto set my hand at New York city, N. Y., this 3d day of January, 1916.

JOHN K. STEWART.
